UNITED STATES PATENT OFFICE.

CARL WEBER, OF BERLIN-WILMERSDORF, GERMANY.

DRIVING AND BRAKING DEVICE, OR RELEASING DEVICE, FOR PHOTOGRAPHIC SHUTTERS.

1,076,253.

Specification of Letters Patent.

Patented Oct. 21, 1913.

Application filed November 30, 1912. Serial No. 734,235.

To all whom it may concern:

Be it known that I, CARL WEBER, a subject of the King of Prussia, residing at Berlin-Wilmersdorf, Germany, have invented 5 new and useful Improvements in Driving and Braking Devices, or Releasing Devices, for Photographic Shutters, of which the following is a specification.

My invention relates to driving and braking devices, or releasing devices, for photographic time and instantaneous shutters having a spring or weight drive for automatically releasing photographic shutters, said drive being regulated by a flowing jet 15 of granular material, say a jet of sand.

According to the invention I provide in the vessel containing the sand two chambers which are formed by a partition containing the outlets for the jet of sand, and the two 20 chambers alternately serve as the upper working chamber containing the outflowing column of sand, and as the lower receiving chamber which catches the outflowing jet of sand, the arrangement being such that simply by swinging the vessel around, without pouring the sand back, the lower receiving chamber can be converted into the upper working chamber, whereupon the device is 25

at once ready for working again. In a preferred form of the invention the vessel is 30 divided into the two chambers by a fixedly arranged partition having the outlet for the jet of sand, and a separate piston is arranged to move in each of the two chambers thus 35 formed, each piston being preferably packed in its chamber. The pistons simultaneously constitute the stoppers of the vessel containing the sand or of the two chambers in the vessel. The pistons may be packed by washers of board or felt or other suitable soft 40

material. The two pistons are preferably connected one with the other by means of a tube which surrounds the sand vessel and can be shifted longitudinally of the same. 45 The sand vessel is arranged to rock about a pivot and may be mounted in a yoke whose spring-pressed or loaded displaceable plate acts on the upper working chamber of the sand vessel, or on the upper piston, or on 50 the pipe firmly connected with this piston, so that the pistons descend under this action but are checked by the column of sand flowing in a fine jet or in several jets out of the upper working chamber into the lower working 55 chamber, and a member which is con-

nected on the one hand with the movable plate of the yoke and on the other hand with the releasing lever of the photographic shutter, actuates the latter in the intended manner after an adjustable predetermined time. 60 The mechanism for regulating the jet of sand works only in the vertical position, so that the device, ready for working, can be moved out of the vertical into the horizontal position, for example, until it is wished to 65 start it working.

When the apparatus is applied to a photographic camera, in order to be able to use it as desired for both vertical and horizontal exposures without having to remove it from 70 the camera, according to one form of the invention the connecting member between the photographic shutter and the part of the releasing device moved under the influence of the sand vessel preferably consists of 75 a flexible wire guided in a flexible cord having one end attached to the camera and its other end to the releasing device. In this arrangement, the sand vessel can be placed vertical both for vertical and for horizontal 80 exposures, thus in its working position, without changing the places of attachment of the flexible hollow cord to the camera.

The device according to my invention can be employed in or arranged for shutters of 85 any desired kind in photographic cameras of any desired construction, and by means of this device objective shutters of a simple kind can be provided with all those arrangements which are accustomed to be provided with expensive objectives of special 90 makes.

Some embodiments of the invention are 95 represented in the accompanying drawings, wherein:—

Figure 1 is an elevation, partly in section, showing my improved releasing device connected with the shutter of a camera, and Fig. 2 is a side elevation of the mechanism shown at the bottom of Fig. 1; Fig. 3 shows a modified construction of the device shown in Fig. 2, and Figs. 4 and 4^a are vertical section and side elevation, respectively, showing a regulating device for the nozzle outlet of the sand vessel; Figs. 5 and 6 are elevation, and elevation partly in section, respectively, showing a modified improved device in its locked position for automatically opening and closing shutters, Fig. 7 is an elevation showing the latter device in the released position.

sition, and Fig. 8 is an elevation showing a modified device for obtaining adjustable instantaneous and time exposures for shutters which suddenly open and close.

- 5 Referring firstly to Figs. 1 and 2, the main driving part consists of a cylinder *a* which is divided into two chambers by a partition *b* conically recessed on both sides. In each of the two chambers in the cylinder *a* is fitted a piston *c*, and each of these pistons has a rod *d* mounted in a cap *f* attached to the ends of a long cylinder *g* surrounding the cylinder *a*. In the outer cylinder *g* are two slots *h* located opposite one another, and the inner cylinder *a* can be shifted relatively to the outer cylinder *g* and also relatively to the pistons *c* along guide rods *i* which enter into these slots and are attached, preferably removably, in the partition *b* of the inner cylinder *a*. The displacement of the pistons in the inner cylinder, or of the inner cylinder relatively to the outer cylinder is regulated and checked by a fine jet of outflowing sand which in the vertical position of the cylinder can pass through a fine nozzle outlet *k*, provided in the partition *b* of the inner cylinder, out of the filled upper chamber into the empty lower chamber, whereupon the piston resting on the column of sand and with it the outer cylinder can descend corresponding to the diminution of sand in the upper chamber. In order to reverse the cylinder in such manner that the cylinder which is full for the time being is placed in the upper position, the cylinders can be rotated about the horizontal ends of the guide rods *i*. Fast on the upper ends of the guide rods is a yoke plate *l*, while a second yoke plate *m* located therebelow is movable on the guide rods, and inserted between the yoke plates *l* and *m* on the guide rods are coil springs *n* which press the movable yoke plate *m* against the upper cap *f* of the outer cylinder and thus load the outer cylinder and with it the pistons *c* attached thereto. In the middle of the movable yoke plate *m* is attached a pin *o* which passes through the upper fixed yoke plate *l*, and to whose upper end is attached one end of a releasing wire *p* preferably guided in a spiral tube *q*. In this embodiment the upper end of the spiral tube *q* is provided with a clamp *r* which, as indicated, serves for attaching the entire device to the base board *s* of a photographic apparatus. The upper end of the releasing wire *p* is then, for example, suspended by means of a hook *t* to the releasing lever *u* of the objective shutter. The elastic tube connection has principally been chosen, instead of a rigid connecting wire, because this kind of connection enables convenient suspension of the device by means of the clamp *r* both in the vertical and also in the horizontal position without removal and reattachment of the device when changing from

a vertical to the horizontal exposure position and reversely of the camera, and, further, enables the device to be stopped, especially before the exposure, simply by placing the cylinders of the mechanism for regulating the jet of sand horizontal. After a predetermined time, determined by the duration of the outflow of the sand from the upper into the lower chamber of the cylinder *a*, the instantaneous shutter of the objective can be actuated with the described device. Thus, *e. g.*, the photographer can photograph himself alone or in a group by means of this device, as the objective shutter is released, after the apparatus and the described releasing device have been adjusted, only after the spring-pressed yoke plate *m* has descended so far, during the descent of the brake mechanism cylinder, that the releasing wire *p* drawn downward with the yoke plate *m* has pulled the releasing lever *u* of the objective into the releasing position of the objective shutter. For regulating the period within which the release is to take place, as shown in Fig. 4 one of the two guide rods may be provided in its lower portion with an adjustable micrometer screw *v* whose point projects into the nozzle outlet *k* of the partition *b* and whose head, formed as a handle, is preferably provided with divisions indicating the duration of release, and, if desired, corresponding designations.

The modification shown in Fig. 3 differs from that described above in that two guide rods *w* are attached on the movable yoke plate *m*; these rods pass freely through the upper fixed yoke plate *l* and their upper ends are connected together by a plate *x* in whose recess *y*, on the one hand, and in a recess in the yoke plate *l*, on the other hand, the push of one of the well-known wire releasing devices *z* can be inserted, in order to be able to employ these well-known wire releasing devices with my improved device.

When the device according to Fig. 3 is modified in a simple suitable manner the same can also be employed for actuating a releasing device controlled by a rubber bulb.

Figs. 5 and 6 show the connection of my improved driving and braking device for photographic time and instantaneous shutters with an automatically opening and closing contrivance for objective shutters which open slowly. With this contrivance it is possible automatically to open the objective shutter after a predetermined time dependent on the time during which the jet of sand flows out, and automatically to close the objective shutter again after a predetermined variable time. For this purpose a tube *1* is firmly connected with the sand jet cylinder *g*, constructed exactly according to Figs. 1 and 2, or with the middle portion of the lower yoke plate *m* which is displaceable against the action of springs *n* on the guide

rods *i*. This tube passes freely through the upper fixed yoke plate *l* and possesses two slots 2 and 3, from each of which projects a pin 4 and 5, respectively, to each of which is attached a metal member 6 and 7, respectively, displaceable in the tube 1. As Fig. 6 shows, the two pieces of metal 6 and 7 are coupled together by a spiral spring 8 which tends to press them apart. In the lower part of the tube is another spiral spring 9 which presses on the lower piece of metal 7. To this lower piece of metal 7 is attached the releasing wire *p* of the wire releaser connected with the contrivance, and this wire *p* passes freely through a bore in the upper piece of metal 6. Outside the tube 1 the wire *p* is guided for a certain distance in a wire spiral *q*, and this spiral *q* terminates, as according to Fig. 1, in a clamp *r* to be attached to the base board of the photographic apparatus, while the releasing wire *p* terminates in a somewhat thicker wire *t* running out into a hook to be suspended from the releasing lever of the objective shutter. The extensions of the guide rods *i* led through the upper fixed yoke plate *l* are provided with screw threads and carry adjustable abutment nuts 10 and 11. In the tensioned position of the device represented in Fig. 5 the two pieces of metal 6 and 7 are arrested against the action of the spring 8 by angular arresting levers 12 and 13, respectively, whose hooked parts have been placed over the pins 4 and 5, respectively. The levers 12 and 13 are fulcrumed on the outside of the tube 1 and are under the action of small wire springs, not shown. In the vertical position of the device, thus when the same hangs vertically downward from the clamp *r*, the tube 1 moves relatively to the plate *l* owing to the operation, described with reference to Fig. 1, in the interior of the brake cylinder *g* under the action of the springs *n*, and consequently the levers 12 and 13 suspended on the tube 1 move against the stops 10 and 11, and after a certain time dependent on the time during which the sand flows out of the cylinder *g* and adjustable by adjusting the stop 10 in height, this stop 10 abuts against the arm of the arresting angle lever 13 within its reach and lifts the hook of this lever from the pin 5 on the piece of metal 7. The piece of metal 7 released thereby can then be pressed downward by the spring 8 between the pieces of metal 6 and 7 against the action of the weaker spring 9, the releasing wire *p* attached to the piece of metal 7 being suddenly drawn downward with the releasing hook and the objective shutter being opened. The objective shutter remains open until the other stop 11 coacts with the arm of the upper arresting angle lever 12 which is in its reach and holds the pin 4. The time of this coaction and with it the

time during which the objective shutter is open can be adjusted by adjusting the stop 11 and can be read at a scale provided suitably on the plate *l*. After the release of the pin 4 the two pieces of metal 6 and 7 coupled together move under the action of the spring 9 into their upper end position shown in Fig. 7, in which the releasing wire *p* connected with the piece of metal 7 and the hook *t* has suddenly released the opening lever of the objective shutter, so that the objective can return into its closed position after the adjusted duration of exposure has expired.

In the form of my driving and braking device according to the invention illustrated in Fig. 8 there is attached on the yoke plate *m* a rod 14 which projects into the interior of a tube 15 fast on the upper yoke plate *l*. In the interior of this tube is a piece of metal 16 coupled by a spring 17 with the plate *l*. On this piece of metal 16 is attached the releasing wire *p* as well as a pin 19 which projects outward through a slot 18 and is held in the illustrated position of the piece of metal 16 by the hook of an angle lever 20. This angle lever 20 is fulcrumed on the rod 14, and the horizontal arm of the lever arrives within reach of the stop 10, adjustable according to a scale, when the plate *m* and rod 14 are shifted when the sand runs into the braking cylinder *g*. After a certain adjustable time has expired, during which the objective shutter has been opened and held open during the descent of the plate *m* with the rod 14 and with it of the releasing wire *p* with the hook *t*, the parts 20 and 10 contact one with another, the pin 19 is thereby released from the hook of the lever 20 and the piece of metal 16, carrying the pin 19, flies up under the action of the spring 17, whereby the releasing wire *p* which has until now been held tensioned and is attached to the piece of metal 16 is loosened, and the objective shutter which has been opened can move into its closed position. This device is intended for suddenly opening and closing objective shutters for obtaining adjustable instantaneous and time exposures whereas, as already mentioned, the arrangement according to Figs. 5 to 7 is intended for slowly opening objective shutters for adjusting instantaneous and time exposures after a certain adjustable time.

I claim:

1. In a device of the character described for controlling photographic shutters, the combination with a member operatively connected to the shutter, of a vessel containing sand, a partition dividing the vessel into two chambers, said partition having an outlet for the sand from one chamber to the other, means movable in the vessel and controlled by the sand flowing from one chamber.

ber into the other, and a member attached to the former member and controlled by said means, said means being returnable into operative relation with the latter member, 5 after the sand has flowed from one chamber to another, without removing the sand into the other chamber.

2. In a device of the character described for controlling photographic shutters, the 10 combination with a member operatively connected to the shutter, of a vessel containing sand, a partition dividing the vessel into two chambers, said partition having an outlet for the sand from one chamber to the other, 15 a piston in each chamber, means rotatably carrying said vessel, and a spring-pressed member slideable on said means, adapted to be controlled by the pistons in turn and attached to the former member.

20 3. In a device of the character described for controlling photographic shutters, the combination with a member operatively connected to the shutter, of a vessel containing sand, a partition dividing the vessel into two 25 chambers, said partition having an outlet for the sand from one chamber to the other, a piston movable in each chamber, means rotatably carrying said vessel, and a spring-pressed member slideable on said means, 30 adapted to be controlled by the pistons in turn and attached to the former member, each piston constituting a stopper of the chamber in which it is movable.

4. In a device of the character described for controlling photograph shutters, the combination with a member operatively connected to the shutter, of a vessel containing sand, a partition dividing the vessel into two chambers, said partition having an outlet 40 for the sand from one chamber to the other, a piston in each chamber, means connecting together the two pistons, means rotatably carrying said vessel, and a spring-pressed member slideable on said means, 45 adapted to be controlled by the pistons in turn and attached to the former member.

5. In a device of the character described for controlling photographic shutters, the combination with a member operatively connected to the shutter, of a vessel containing sand, a partition dividing the vessel into two chambers, said partition having an outlet 50 for the sand from one chamber to the other, a piston in each chamber, a tube surrounding said vessel and connecting together the two pistons, means rotatably carrying said vessel, and a spring-pressed member slideable on said means, adapted to be controlled by the pistons in turn and attached to the former 55 member.

6. In a device of the character described for controlling photographic shutters, the combination with a member operatively connected to the shutter of a vessel containing 60 sand, a partition dividing the vessel into two

chambers, said partition having an outlet for the sand from one chamber to the other, a piston in each chamber, means rotatably carrying said vessel, and a spring-pressed member slideable on said means, adapted to be controlled by the pistons in turn and attached to the former member, the axis of rotation of the vessel passing through said partition.

7. In a device of the character described for controlling photographic shutters, the combination with a member operatively connected to the shutter, of a vessel containing sand, a partition dividing the vessel into two chambers, said partition having an outlet 70 for the sand from one chamber to the other, a piston in each chamber, a cylinder surrounding said vessel and connecting together the said pistons, means comprising a yoke and two rods attached at one end thereto 75 carrying said vessel at their other ends, and a plate movable on said rods, normally spring-pressed against one end of said cylinder, and attached to said member.

8. In a device of the character described for controlling photographic shutters, the combination with a member operatively connected to the shutter, of a vessel containing sand, a partition dividing the vessel into two chambers, said partition having an outlet for 80 the sand from one chamber to the other, a piston in each chamber, a cylinder surrounding said vessel and connecting together the said pistons, means comprising a yoke and two rods attached at one end thereto, 85 a regulating screw carried by the other end of one rod and projecting into said outlet, said vessel being rotatably carried by said screw and by the other end of the other rod, and a plate movable on said rods, normally 90 spring-pressed against one end of said cylinder, and attached to said member.

9. In a device of the character described for controlling photographic shutters, the combination with a wire operatively connected to the shutter, of a vessel containing sand, a partition dividing the vessel into two chambers, said partition having an outlet 95 for the sand from one chamber to the other, a piston in each chamber, a cylinder surrounding said vessel and connecting together the said pistons, means comprising a yoke and two rods attached at one end thereto 100 rotatably carrying said vessel at their other ends, a tube surrounding said wire and attached to said yoke, and a plate movable on said rods, normally spring-pressed against one end of said cylinder, and attached to said wire.

10. In a device of the character described for controlling photographic shutters, the combination with a wire having one end 110 operatively connected to the shutter, a member attached to the other end of the wire, of a vessel containing sand, a partition dividing the vessel into two 115

the vessel into two chambers, said partition having an outlet for the sand from one chamber to the other, a piston in each chamber, a cylinder surrounding said vessel and connecting together the said pistons, means comprising a yoke and two rods attached at one end thereto rotatably carrying said vessel at their other ends, a plate movable along said rods and normally spring-pressed 10 against one end of said cylinder, and a yoke carried by said plate and adapted to hold said member between itself and the former yoke.

11. In a device of the character described 15 for controlling photographic shutters, the combination with a wire having one end operatively connected to the shutter, a cord surrounding the wire, a slotted tube having one end attached to the cord, a piece of metal 20 movable in the tube and attached to the other end of the wire, a pin carried by the piece of metal and projecting out of the slot in the tube, an angle lever fulcrumed on

the tube and having one arm normally engaging said pin, a yoke carrying the other 25 end of the tube, a stop adjustably carried by the yoke and adapted to coact with the other arm of the angle lever and release the pin from the former arm, and a spring normally compressed between the piece of 30 metal and the yoke, of a vessel containing sand, a perforated partition dividing the vessel into two chambers, a piston in each chamber, two rods attached to said yoke and rotatably carrying said vessel, a cylinder surrounding and longitudinally of the vessel, a plate movable along said rods and normally resting against one end of the cylinder, and springs surrounding said rods tending to push said yoke and said plate apart. 35

In testimony whereof I affix my signature in presence of two witnesses.

CARL WEBER.
